PUMP FOR GRANULAR PASTE-LIKE MATERIALS SUCH AS CONCRETE

Paul August Reinmud Frank, Hamburg,
GermanyApplication December 31, 1931, Serial No. 584,303
In Germany January 2, 1931

10 Claims. (Cl. 103—163)

The invention relates to pumps for pumping granular, paste-like materials such as concrete.

The pumps hitherto known for pumping concrete and like material almost invariably embody 5 pump-valves which give rise to interruptions or break-downs during operation. Further the working of the pumps hitherto known for concrete or like materials is very liable to be affected by non-uniformity in the mix.

10 The disadvantages of the known kinds of pumps are avoided by the present invention. This is effected more particularly in that no pump-valves or the like are used as well as in that all parts of the pump are so constructed in 15 special consideration of the composition of the material consisting of a mixture of paste and lumps which has to be pumped that smaller or larger particles contained in the paste cannot obstruct the moving elements of said pumps 20 while said elements are performing their motion.

According to the invention, during the idle stroke, apertures which are provided in a hollow cylindrical carrier surrounding the piston of the pump and partially movable together with that 25 piston are put in communication for a predetermined space of time with the pressure chamber of the pump. The material passes through these openings into the pressure chamber when the piston is withdrawn from the pressure chamber.

30 After the piston is withdrawn from the pressure chamber the cylinder carrying the apertures is displaced to position the apertures outside the pressure chamber where they are closed by the piston. Beneath the pressure chamber a slide 35 plate or the like is provided which during the idle stroke of the piston and of the apertured carrier closes the pressure chamber, is opened during the working stroke and again closes the pressure chamber after completion of the working stroke. Preferably a container is provided 40 which serves to receive a quantity of the material which is to be pumped, which quantity is maintained constant, the conduit through which the material is pumped being connected with the 45 chamber by a socket constituting the pressure chamber of the pump and surrounding in part both the piston and the apertured hollow cylinder carrier. The slide plate disposed beneath the pressure chamber is preferably so arranged that 50 when it is closed on the completion of the working stroke it passes close to the lower surface of the working piston and to the lower edge of the hollow cylinder surrounding the piston so that it separates the pumped material from the bottom 55 of the piston and from the end of the tube

and again closes the pressure chamber of the pump. In this arrangement of the slide plate its motion cannot be obstructed by larger particles present in the material. The motions of the piston, of the hollow cylinder surrounding the 60 same and of the slide plate are preferably derived automatically and positively from a control device such as a cam disc for example.

One embodiment of the invention is shown 65 partly in schematic representation in the accompanying drawings which show by way of example a pump with a vertically reciprocating piston.

Fig. 1 shows a partial section of the arrangement in initial position.

Figs. 2 to 8 show various positions of the moving parts (i. e., the piston of the pump, the hollow cylinder surrounding the piston and the slide plate) during a complete cycle, comprising idle stroke and working stroke, of the arrangement of Fig. 1.

Fig. 2 shows the piston in somewhat raised position.

Fig. 3 shows the piston in a more raised position.

Fig. 4 shows a third raised position of the piston 80

Fig. 5 shows a still more raised position of the piston in which the hollow cylinder is also raised.

Fig. 6 shows a lower position of the piston with the hollow cylinder still raised.

Fig. 7 shows a lower position of the piston and 85 of the hollow cylinder with the slide plate in the open position,

Fig. 8 shows the end position of the piston and hollow cylinder with slide plate still in the open position.

Fig. 9 shows an arrangement with two pump units one of which is shown in section and the other in elevation as seen in a direction at right angles to the remaining figures.

A shaft C is journalled in bearings D and E at 95 the top of a framework A (Figs. 1 and 9). A driving pulley F is secured on the free end of the shaft 2. Further a container a is disposed within the frame A and contains the granular paste like material B containing larger particles which is to be pumped, for example the concrete. The quantity of concrete in the container a is maintained constant by known means so that it always fills the container to the same level. At the bottom of the container is provided a pipe socket b which surrounds the pressure chamber G of the pump. A hollow cylinder c fitting the pipe socket b projects into the pressure chamber of the pump and surrounds the piston d of the pump. At the bottom, the pressure chamber G of the pump is closed 105

by means of a slide plate *e* which as shown in Figs. 1 and 9 lies close against the lower edge of the piston *d* and the hollow cylinder *c* as well as the socket *b* in the starting position i. e., before each idle stroke and after each working stroke. The pipe *f* through which the material is conveyed is attached beneath the slide plate.

The hollow cylinder *c* is provided with peripheral slot shaped apertures *c*¹ the lower edges of which are disposed at the level of the bottom of the container *a* in the starting position of Fig. 1.

An eccentric or cam disc *g* is mounted on the shaft *C* and rotates therewith. It is provided with cam grooves *d*², *c*³, *e*³ in which run corresponding rollers *d*¹, *c*², *e*². The roller *d*¹ is connected with the piston *g* which is movable up and down. The roller *c*² is mounted on the hollow cylindrical carrier of the apertures *c*¹ which is also movable up and down. The roller *e*² is carried on a lever *e*¹ which at its lower end is connected with the laterally movable slide plate *e*. The lever *e*¹ is pivoted to the frame *A* at *e*⁴.

The frame carries a guide *H* which guides the hollow cylinder *c* during its longitudinal displacement. The guide *H* is connected to the frame by means of an arm *I* and a clamp *K* or the like.

The piston *d* is preferably constructed as a hollow piston. It may be provided at the bottom with an air valve which opens only when the piston is executing an upward motion.

The motions of the piston *d*, the hollow cylindrical carrier *c* of the openings *c*¹ and the slide plate *e* are executed automatically and positively during the rotation of the cam disc *g*.

Fig. 1 shows the starting position in which the valve *e* is closed; the piston *d* and the hollow cylinder *c* are in their lowest positions and are in contact or almost in contact with the slide plate *e*. In Fig. 2, in consequence of the rotation of the cam disc *g*, the piston has been raised somewhat after the pump has been set in operation. A vacuum of greater or less degree is formed between the bottom of the piston *d* and the slide plate *e*, i. e., in the pressure chamber *G* of the pump. When in its further upward motion, as shown in Fig. 3, the piston *d* is raised to such an extent that its lower edge is above the lower edge of the apertures *c*¹ in the hollow cylinder *c*, then the concrete begins to flow in through the apertures *c*¹ into the pressure chamber *G* of the pump. This flow attains its full magnitude as soon as the lower edge of the piston has completely cleared the apertures *c*¹ as shown in Fig. 4. The material passing into the pressure chamber *G* of the pump or into the interior of the hollow cylinder *c* continues to flow into this space until the material inside the pump stands at the same level as it does outside in the container *a* (Fig. 5).

Immediately before this, in consequence of the shape of the corresponding cam, the hollow cylinder *c* is also lifted to such an extent that the lower edges of the apertures *c*¹ are above the surface of the material (Fig. 5). The lower edge of the hollow cylinder *c* is then about at the level of the bottom of the container *a*. The pipe socket *b* surrounding the pressure chamber *G* of the pump and the hollow cylinder *c* are now filled up to a level corresponding to the surface of the concrete mix *B* with the material which is to be pumped. The pressure chamber of the pump is still closed by the slide plate *e*.

In the further rotation of the cam disc *g* the piston *d* is moved downwardly and in the first place closes the apertures *c*¹ (Fig. 6) and compresses the air which is above the material in the

hollow cylinder *c*. In this way an air cushion serving as a buffer is obtained which prevents the reaction of too heavy a pressure on the gearing. Alternatively resilient devices could be provided in the drive of the piston *d*.

80

After the apertures *c*¹ are closed, the slide plate *e* is moved into the open position in consequence of the configuration of the corresponding cam *e*². The material to be pumped is then forced into the conduit *f* by the continued downward motion of the piston *g*. Piston *d* and hollow cylinder *c* move downwardly together (Fig. 7) until they have attained the lowermost position (Fig. 8) which corresponds to the starting position of Fig. 1. In consequence of the shape of the cams they remain in this position for a period until the slide plate *e* has again moved into the closed position.

90

This closure can be effected without encountering too great a resistance due to particles which may be present in the material because the slide member passes closely adjacent to the lower surface of the piston and lower edge of the hollow cylinder and thus separates the pumped material from the bottom of the pump piston and from the edge of the cylinder. The working operation consisting of idle stroke and working stroke can then be repeated.

95

The double arrangement of Fig. 9 is differentiated from the simpler arrangement of the remaining figures only in that a larger container *a* is provided from which two pumps of the kind described are supplied with the material which is to be pumped.

100

The particular advantage of pumps according to the present invention resides in that mixes of every kind can be pumped, in particular all kinds of concrete mixes such as are used for reinforced concrete constructions. It is completely impossible for the feed path within the pump to be blocked.

115

Means other than the cam disc could be used for occasioning the automatic motions of the piston, hollow cylinder and slide plate; for example connecting links, grooved rollers, friction discs or the like could be used.

120

I claim:

1. A pump for lumpy paste-like materials, comprising a pressure chamber, a piston movable into and partly out of said pressure chamber, a cylindrical member surrounding said piston and likewise movable into and partly out of said pressure chamber, said cylindrical member also being movable partially together with said piston, said cylindrical member having apertures therein in connection with said pressure chamber for passing the material into the pressure chamber when said piston is withdrawn from said chamber, said piston closing said apertures to break connection with said pressure chamber, a pipe line connected to said pressure chamber, and movable means adjacent the ends of said piston and said cylindrical member when in their extreme position, for moving transversely thereacross and coming between them and the material in the pipe line for closing said pipe line against said pressure chamber.

125

2. A pump for lumpy paste-like materials, comprising a pressure chamber, a hollow cylinder movable into and partly out of said pressure chamber, a piston slidable within said hollow cylinder and likewise movable into and partly out of said pressure chamber and said piston also being movable partially together with said hollow cylinder, said hollow cylinder being adapted to be connected with the source of material to

130

135

140

145

150

- afford a passage for said material into said pressure chamber, a pipe line connected to said pressure chamber, and movable means adjacent the ends of said piston and said cylindrical member 5 when in their extreme position, for moving transversely thereacross and coming between them and the material in the pipe line for closing said pipe line against said pressure chamber.
3. A pump for lumpy paste-like materials, comprising a pressure chamber, a piston movable into and partly out of said pressure chamber, a cylindrical member surrounding said piston and likewise movable into and partly out of said pressure chamber, said cylindrical member 10 also being movable partially together with said piston, said cylindrical member having apertures therein for connection with said pressure chamber for passing the material into the pressure chamber when said piston is withdrawn from said chamber, said apertures being adapted to be closed by said piston to break the connection with said pressure chamber, a pipe line connected to said pressure chamber, and a slide plate adjacent the ends of said piston and said cylindrical member 15 when in their extreme position, for moving transversely thereacross and coming between them and the material in the pipe line for closing the pressure chamber against said pipe line during the idle stroke of said piston from the bottom of said piston and from the end of said cylindrical member.
6. A pump for lumpy paste-like materials, comprising a pressure chamber, a piston movable into and partly out of said pressure chamber, a cylindrical member surrounding said piston and likewise movable into and partly out of said pressure chamber, said cylindrical member further also being movable partially together with said piston, said cylindrical member having apertures therein for connection with said pressure chamber for passing the material into the pressure chamber when said piston is withdrawn from said chamber, said apertures being adapted to be closed by said piston to break the connection with said pressure chamber, a pipe line connected to said pressure chamber, a slide plate for closing the pressure chamber against said pipe line during the idle stroke of said piston and of said cylindrical member, said slide plate being open during the working stroke of the piston to connect said pressure chamber with said pipe line and being closed after completion of the working stroke of said piston, a container for the material to be pumped, said pressure chamber comprising a socket connecting said container with said pipe line, said container partially surrounding the cylindrical member adjacent the apertures therein, said slide plate being disposed beneath said socket and passing closely adjacent the lower edge of said piston and the surrounding cylindrical member when in their lowermost position, said slide plate being adapted upon the closing movement to separate the pumped material from the bottom of said piston and from the end of said cylindrical member.
4. A pump for lumpy paste-like materials, comprising a pressure chamber, a piston movable into and partly out of said pressure chamber, a cylindrical member surrounding said piston and likewise movable into and partly out of said pressure chamber, said cylindrical member also being movable partially together with said piston, said cylindrical member having apertures therein for connection with said pressure chamber for passing the material into the pressure chamber 40 when said piston is withdrawn from said chamber, said apertures being adapted to be closed by said piston to break the connection with said pressure chamber, a pipe line connected to said pressure chamber, a slide plate adjacent the ends 45 of said piston and said cylindrical member when in their extreme position, for moving transversely thereacross and coming between them and the material in the pipe line for closing the pressure chamber against said pipe line during the idle stroke of said piston and of said cylindrical member, said slide plate being open during the working stroke of the piston to connect said pressure chamber with said pipe line and being closed after completion of the working stroke of said piston, a container for the material to be pumped, said pressure chamber comprising a socket connecting said container with said pipe line, said container partially surrounding the cylindrical member adjacent the apertures therein, said slide plate being disposed beneath said socket and passing closely adjacent the lower edge of said piston and the surrounding cylindrical member when in their lowermost position, said slide plate being adapted upon the closing movement to separate the pumped material from the bottom of said piston and from the end of said cylindrical member.
5. A pump for lumpy paste-like materials, comprising a pressure chamber, a piston movable into and partly out of said pressure chamber, a cylindrical member surrounding said piston and likewise movable into and partly out of said pressure chamber, said cylindrical member also being movable partially together with said piston, said cylindrical member having apertures 55 thereto.
7. A pump for lumpy paste-like materials, comprising a pressure chamber, a piston movable into and partly out of said pressure chamber, a cylindrical member surrounding said piston and likewise movable into and partly out of said pressure chamber, said cylindrical member movable partially together with said piston, said cylindrical member having apertures provided therein for connection with said pressure chamber for passing the material into the pressure chamber when 60 said piston is withdrawn from said chamber, said apertures being adapted to be closed by said piston to break the connection with said pressure chamber, a pipe line connected to said pressure chamber, a slide plate for closing the pressure chamber against said pipe line during the idle stroke of said piston and of said cylindrical member, said slide plate being open during the working stroke of the piston to connect said pressure chamber with said pipe line and being 65

closed after completion of the working stroke of said piston, said slide plate being disposed beneath said pressure chamber and passing closely adjacent the lower edge of the piston and the 5 surrounding cylindrical member, said slide plate, upon the closing movement thereof, separating the pumped material from the bottom of said piston and from the end of said cylindrical member, and a controlling device adapted to control 10 the motions of said piston, said surrounding cylindrical member when in their lowermost position and said slide plate in a positive and automatic manner.

8. A pump for lumpy, paste-like materials, 15 comprising a piston, a hollow cylindrical carrier surrounding said piston and movable in part together therewith, a pressure chamber, the said carrier having apertures therein for connection with the said pressure chamber, the piston extending through said cylindrical carrier into said pressure chamber and being movable into and partially away from said pressure chamber so that when it is partially withdrawn therefrom, the material passes into the pressure chamber 20 through the apertures, the apertures being closed by movement of the cylindrical carrier outwardly of the pressure chamber, a slide plate, a pipe line, and means for moving said slide plate to maintain the pressure chamber closed 25 during the upward movement of the piston and the cylindrical carrier and to maintain the pressure chamber open into communication with said pipe during the downward stroke of the piston, the slide plate, when closing the pipe, being movable closely adjacent the lower edge of the 30 piston and cylinder, thus shearing the pumped material from the bottom of the piston and the end of the cylinder, and closing the pressure chamber of the pump.

35 9. A pump for lumpy, paste-like materials, comprising a container for the material, a pres-

sure chamber, a piston movable in said pressure chamber, a cylindrical carrier surrounding said piston and extending through said container, and likewise movable in said pressure chamber, the said cylindrical member having means therein 80 adapted to connect the container with the pressure chamber, a pipe line adapted to connect the said pressure chamber, a plate slideable transversely across the junction between said pressure chamber and said pipe, and a single means for actuating said piston, said cylindrical member and said plate, the said means moving said slide to close the pipe only when it has brought the piston and the cylindrical member to a position with their bottommost edges substantially 85 into contact with the surface of said plate.

10. A pump for lumpy, paste-like materials, comprising a container for the material, a pressure chamber, a cylindrical member extending through said container and slideable in said pressure chamber, and having apertures therein 90 adapted to connect the container with the pressure chamber, a piston extending through said cylindrical member into said pressure chamber, and adapted to first open said apertures to fill the pressure chamber and to thereafter seal said apertures and to expel the material in said pressure chamber, a pipe communicating with said pressure chamber, a plate slideable transversely across said pipe to seal it against said pressure 100 chamber and a cam common to said piston, said cylindrical member and said plate for automatically actuating the same, and for moving said plate into its closed position only when both the piston and the cylindrical member have their 105 lowermost edges adjacent the surface thereof, so that the plate exercises a shearing action on the pumped material adhering to the surface of the piston and the cylindrical member.
